COIN HOLDER FOR KEY CHAINS AND THE LIKE

Walter G. Nauman, Milwaukee, Wis.

Application May 14, 1952, Serial No. 287,794

1 Claim. (Cl. 286—81)

2

With the above and other objects in view, which will more readily appear as the nature of the invention is better understood, the same consists in the novel construction, combination and arrangement of parts hereinafter more fully described, illustrated and claimed.

A preferred and practical embodiment of the invention is shown in the accompanying drawings.

In which drawings:

Figure 1 is a top plan view of my novel coin holder affixed to a key chain, certain parts being broken away to better illustrate various details of construction;

Figure 2 is a side elevational view of my coin holder showing in particular how it is held to the ball key chain;

Figure 3 is an end elevational view of my device showing the coin holder in the same position on the key chain as illustrated in Figures 1 and 2 of the drawings;

Figure 4 is a vertical longitudinal section through my coin holder, the section being taken on the line 4—4 of Figure 1 and looking in the direction of the arrows;

Figures 5, 6, 7, and 8 are enlarged fragmentary longitudinal sectional views illustrating the successive steps necessary to secure my novel holder to a conventional key chain;

Figure 9 is an enlarged fragmentary transverse sectional view taken on the line 9—9 of Figure 1 and showing in particular the inner bevel of the edges of the slot; and

Figure 10 is a similar enlarged fragmentary transverse section through the holder taken on the line 10—10 of Figure 1 and looking in the direction of the arrows.

Referring now to the drawings in detail, wherein similar reference characters designate corresponding parts throughout the several views, the letter "H" generally indicates one type of my improved coin holder and the same shown secured to a conventional key chain "K."

As stated, the key chain is of the conventional type and includes a series of balls 20 connected by the small links 21 and provided with the snap fastener 22.

While my coin holder "H" may be made from any desired material, in the preferred form I use a clear transparent plastic and the same is molded to form an elongated receptacle 23 of a size and configuration to receive the coins "C." The receptacle 23 includes top and bottom walls 24 and 25 respectively which are joined by the side walls 26 and 27 as shown. The receptacle 23 may be of any desired shape or configuration to hold the coin "C" but I prefer to form the same with rounded rear and front ends 28 and 29 respectively. The rear end 28 is provided with a small slot or opening 30, the main purpose of which is to enable the body to be molded in one piece and easily removed from the dies. The front end 29 however, is purposely opened and it is to be noted that the sides 26 and 27 respectively terminate substantially short of the forward end 29 to form an open space 31 between the top wall 24 and the bottom wall 25. It is into this space 31 that the coins may be placed and received in the receptacle 23 and the outer forward ends 29 of the top and bottom walls 24 and 25 respectively should be flexible and resilient enough to permit bending toward one another under pressure without breaking and to resume their normal positions when the pressure is released. The reason for this will be readily apparent as the description proceeds.

The top and bottom walls, at the forward open end thereof, are each provided with longitudinally extending centrally positioned aligned slots 32 and 32'. The slots 32 and 32' open out on the end 29 and extend inwardly to terminate adjacent a point intermediate the outer ends 33 of the side walls 26 and 27.

It is obvious that the slots 32 and 32' may open out at any point along the outer edge of the end 29, however, in the preferred embodiment I positioned the

This invention appertains to coin holders and more particularly to a novel coin holder adapted to be affixed to a key chain and which is an improvement over the coin holder and key chain combination set forth in my co-pending application, Serial No. 278,064, filed March 22, 1952.

The coin holder disclosed in my co-pending application is designed primarily for use as an emergency coin holder for coins of the denomination now used generally in parking meters and pay telephones. Briefly, my prior coin holder included a flat elongated receptacle body open at one end to receive the coins and which open end is provided with a round aperture therethrough, sufficiently large enough so as to freely receive the balls of a ball key chain and a restricted slot communicating with the round aperture at one end and opening out at the other end of the coin holder. The restricted slot is only of a sufficient width to receive the links between the balls. In this prior device it is necessary to modify the key chain so as to provide an elongated reduced portion between the balls which must be aligned with the restricted slot in order to attach or remove the holder from the chain.

The coin holder of the present invention is designed for similar use as an emergency holder but one which may quickly and readily be applied to or detached from a conventional key chain without the necessity of opening the key chain's snap fastener or modify the key chain in any way.

A salient feature of the present invention resides in the fact that the coin holder may be attached to the key chain without necessitating any modification of the chain per se and when so attached will hold its position on the chain and can not be accidentally detached therefrom.

Another object of my invention is to provide means on one end of my novel holder whereby it may be applied to the chain by bending or camming the ends of the holder between any two balls on the chain without the necessity of lining up any particular portion of the key chain.

A more specific object of my invention is to provide a flat elongated key holder, the open end of which is provided with a restricted slot on its top and bottom wall, the width of which is slightly larger than the width or diameter of the links of the ball key chain, the side edges of the restricted slot having a taper or bevel whereby the respective balls of the ball key chain will ride on the bevel and cam the outer ends of the top and bottom walls inwardly as the holder is being applied to the chain.

A further important object of my invention resides in the fact that the inner end of each restricted slot terminates in a semi-spherical recess which receives the respective portions of the balls on the key chain and will firmly hold my coin holder in its locked position.

A still further object of the invention is to provide a new and novel coin holder of the key chain type which is of an attractive appearance and of a comparatively small size, and one which can be placed upon the market at a reasonable cost and one which will be durable and efficient in use.

aligned slots 32 and 32' so that they open out centrally on the end 29. The opposed edges of the slots 32 and 32' are each provided with a tapered top and bottom to form a bevel 34 which becomes deeper towards the outer end of the slot.

The inner end of each slot 32 and 32' terminates in a semi-spherical recess 35 as shown, one recess is formed in the upper surface of the top wall 24 and one in the lower surface of the bottom wall 25.

As shown more clearly in Figures 5 to 8 inclusive, the top edges of the slot 32 and the under edges of the slot 32' are tapered or beveled at 36 starting adjacent the semi-spherical recesses 35 and the taper becomes deeper towards the outer end 29. Although it is not absolutely necessary, I prefer to also taper the inner edges of the top and bottom walls 24 and 25 as indicated by the numeral 37.

The reason for the tapers 36 and 37 forming the bevels 34 will be clearly apparent from the following description of the preferred manner for attaching and detaching my coin holder "H" forming key chain "K."

Referring now in particular to Figures 5 to 8 inclusive of the drawings, it can be seen that, in order to attach my novel coin holder "H" to a conventional key chain "K," it is merely necessary to stretch the chain between fingers so as to present a straight portion of the chain to the open end 29 of my coin holder "H" with one of the balls 20 centrally aligned with the opened space 31. The end 29 is then brought into engagement with the key chain "K" and one of the balls 20 will be received in the space or opening 31 and the adjacent link portions 21 will be received in the open ends of the slots 32 and 32' as illustrated more particularly in Figures 5 and 6. The chain and coin holder are then further moved toward each other in the direction of the arrows and it is to be noted that the taper portions 36 engage the respective opposed surfaces of the balls 20 and the top and bottom walls 24 and 25 respectively are cammed inwardly as shown by Figures 6 and 7. The chain continues to move inwardly until the opposed portions of the balls 20 snap into and are received in the respective semi-spherical recesses 35. The resilient outer ends 29 of the top and bottom walls 24 and 25 then resume their normal position except that I prefer to keep the ends 29 of the top and bottom walls under a slight tension so that the device will be firmly locked to the key chain "K" and will not, therefore, be accidentally detached. However, in order to remove the coin holder "H," it is merely necessary to again straighten the key chain and, grasping the coin holder in the other hand, to give a quick jerk. The balls will then be pulled out of the recesses 35 and off the end 29 to release the coin holder "H" so that the coin "C" may be removed.

It is obvious, of course, that I may eliminate the bevels 34 and the tapers forming the same and manually press

55

the resilient outer ends 29 of the top and bottom walls 24 and 25 together so that they will ride under the opposed faces of the balls 20, the ball 20', of course, will be received in the space 31. However, as most conventional ball key chains come in various sizes, I prefer to taper the inner and outer edges at 36 and 37 as shown so that regardless of the spacing of the balls 20, there will always be room to accommodate the center ball 20' in the space 31 and, of course, it will be unnecessary to manually press the top and bottom walls together as this will be done automatically by the camming action of the tapers 36.

From the foregoing, it is believed that the features and advantages of the invention will be readily apparent to those skilled in the art and it will, of course, be understood that changes in the form, proportions, and minor details of construction may be resorted to without departing from the spirit of the invention or the scope of the appended claim.

I claim:

In combination with a key chain having a series of spaced balls joined by thin elongated links, a coin holder comprising, a relatively thin elongated body having integral top, bottom and side walls defining a receptacle therein opened at one end, said side walls terminating short of the top and bottom walls forming resilient end portions at the open end of said body, said top and bottom walls each having an aligned centrally disposed longitudinal slot therein opening out on the open end of said body, the opposed edges of each slot being beveled, said bevels being deeper at the open ends of said slots, the inner end of each slot terminating in a semi-spherical recess of a size and configuration to receive a respective portion of a ball of said key chain, said semi-spherical recesses each extending into the respective top and bottom wall for approximately one-half the thickness of said wall, said slots each being of a size and configuration to receive said links of said ball chain but of a lesser width than the diameter of said balls, whereby the opposed surfaces of any two balls will ride on the beveled surfaces of said slots with the adjacent links of said ball chain received in said slot to cam the resilient ends of said top and bottom walls toward one another and be received in the semi-spherical recess to firmly secure the coin holder to said chain.
